United States Patent Office.

GERARD SICKELS, OF BOSTON, MASSACHUSETTS.

Letters Patent No. 62,159, dated February 19, 1867.

IMPROVED ADJUSTABLE RACK OR SHELF.

The Schedule referred to in these Letters Patent and making part of the same.

Be it known that I, GERARD SICKELS, of Boston, in the county of Suffolk, and State of Massachusetts, have invented a new and improved Portable, Adjustable Rack or Shelf, for hanging clothes, &c., or for holding articles, of which the following is a full, clear, and exact description, reference being had to the accompanying drawings, making part of this specification, in which—

Figure 1 represents a perspective view; and

Figure 2 a side view of my device when closed.

The object of my invention is to provide a light, cheap, and portable device for hanging clothes, towels, &c., to be dried, or for holding any article that may be placed thereon, and the invention consists of a folding rack, so constructed that it may be dropped from a horizontal to a vertical position, and easily folded in a small space. When open it may be suspended against the side wall of a room, or outside of a window or other convenient place, a part being made to project horizontally, or may be arranged at any inclination, the projecting part being provided with rods or bars or with a plane surface, as occasion may require.

Referring to the drawings, A A represent upright bars or standards, joined together by two cross-bars, b b, as shown. To the upper bar b is secured, so as to turn freely, the ends of supports, B, the opposite ends being similarly attached to a swinging frame, C C. The frame C C is composed of two side pieces, connected together by a series of rods or bars, C. The inner ends of the bars C C are made to fit in notches formed in the uprights A, so that when placed in a horizontal position with the ends in the said notches, it will, by means of the bar C, be firmly held, and clothes, towels, or other similar articles, may be hung upon the rods C. Instead of the rods C, a board may be substituted, so as to form a shelf to place either small or large articles upon, or the boards may simply rest upon the rods. It is designed to suspend the device upon the wall or from a window or other place to suit the convenience or purpose of the person using it. h h represent hooks attached to a wall or partition, W, upon which the device may be suspended, by means of the upper cross-bar b''. Instead of placing the frame C C at right angles to the uprights A, it may be arranged at any other angle for the convenience of papers, engravings, &c., by making notches in the standards to suit any inclination. It is equally adapted for use in the kitchen, chambers, or rooms of a house, or for a library or gentleman's office, as it may be found necessary sometimes to have a shelf in a convenient position for the temporary lodgment of books, papers, or other articles where a stationary shelf would be in the way as a fixture; for its position may be changed as required to various parts of a room, and, when not in use, it can be readily folded up in a small compass and placed out of the way, and in transportation a large number can be packed together in a small space. It may also be made to rest upon the floor, and the uprights being properly secured to the wall or other place, the frame C, with a proper covering, may answer the purpose of a seat, and be permanently or temporarily attached to the wall or other suitable place. The device will also be found especially adapted for use in drying shoes or stockings that have been wet during the day, by arranging it over a stove or range or fire-place at night, and placing the said boots or shoes on the bars of the horizontal frame C C. The uprights A may be provided with a base or feet, and a swinging frame may be attached to the other side of the device, if desirable, or two frames may be temporarily connected together to operate in the same manner.

I am aware that a shelf or its equivalent has been pivoted to standards with a hinged supporting brace, and made detachable at one end beneath; this I do not claim, but having thus described my invention, what I claim as new, and desire to secure by Letters Patent, is—

The swinging frame C C, in combination with the standards A A and supporting bars B B, when constructed and operating as and for the purpose set forth.

In testimony whereof I have signed my name to this specification in the presence of two subscribing witnesses.

GERARD SICKELS.
